ATTORNEY

UNITED STATES PATENT OFFICE

EMANUEL WILBANKS, OF STAMFORD, CONNECTICUT

RUMBLE-SEAT TOP

Application filed June 6, 1928. Serial No. 283,315.

My present invention has reference to automobiles of the roadster type, and which are provided with rumble seats, and my object is to provide a protective top for the rumble seats of such type of automobiles.

A further object is the provision of a top for this purpose which is adjustable so that the same can be readily arranged upon the rumble compartment of various sizes of automobiles, and which is collapsible so that the same may be folded into a small package and arranged in a case therefor so that the same can be readily positioned in the rumble seat compartment of the machine when not desired for use.

A further object is the provision of a device for this purpose which shall be of a simple construction, comprising few parts, but which is strong and sturdy when in set up condition and which is readily removable and collapsible when not desired for use.

The invention will be fully and comprehensively understood from a consideration of the following detailed description when read in connection with the accompanying drawings which form part of the application, with the understanding, however, that the improvement is capable of extended application and is not confined to the exact showing of the drawings nor to the precise construction described and, therefore, such changes and modifications may be made therefrom as do not affect the spirit of the invention nor exceed the scope thereof as expressed in the appended claims.

In the drawings:

Figure 1 is a side elevation illustrating the application of my improvement.

Figure 2 is a perspective view of the improvement per se, the curtain and the rumble seat being indicated by the dotted lines.

Figure 3 is a plan view with parts in section showing the device collapsed and arranged in the case therefor, the latter being indicated by the dotted lines.

Figure 4 is a transverse sectional view through the lapping portions of the fabric top of the improvement.

Figure 5 is a sectional view taken through

one of the side members of the improvement in a line with the attaching strap.

Referring now to the drawings in detail, the numeral 1 designates a roadster type of automobile, 2 the rumble compartment at the rear thereof, 3 the rumble seat and 4 the back for the seat.

The top 5 of the roadster, at the rear thereof, is provided with spaced snap elements of the usual construction.

My improvement contemplates the employment of a back frame and a top frame. The back frame comprises side members 6 each in the nature of an angle member. These sides 6 may be constructed of any desired material, 65 light strong metal preferred. The side members 6 have the tops thereof rounded toward the top thereof, as at 7. What I will term the inner flanges of the sides 6, and which for distinction are indicated by the numeral 8, are 70 provided with elongated slots or openings 9. Above these slots there are pivoted to the said portions 8, as indicated by the numeral 10, cross braces 11-11. These flat braces are centrally pivoted together, as at 12, and the 75 free ends of the said braces have passed therethrough short bolt members which also pass through the slots 9 and these bolt members 13 are engaged by wing nuts 14. The construction as so far described permits of the side 80 members 6 being adjusted with respect to each other through the medium of the brace elements 11, and effectively locked by the engaging nuts and bolts when so adjusted. Also the arrangement permits of the said side 85 members being moved toward and almost in contacting engagement when the device is not required for use. The side members from the lower portions thereof have their inner faces provided with compressible strips 15, 90 and these strips are designed to contact with the outer corners and sides of the rumble seat 3 and will not inflict injury thereto.

The outer flanges of the angle sides 6 are provided each with a guide element 16 for a strap 17 which is arranged around the frame and which is likewise arranged around the back 4 of the rumble seat, the split strap having its ends adjustably connected by a buckle 18. The strap is mainly employed for hold- 100

ing the side members of the outer frame, against the outer corners of the rumble seat to permit of the said rear frame member having its sections properly adjusted and likewise to permit of the upper frame member having its sections also properly adjusted and the ends thereof arranged over the top of the automobile. While the ends of the strap are passed through the guides 16, this is mainly for sustaining the strap in proper position on the rear frame members and likewise to provide a means whereby the strap cannot become lost. After the strap has accomplished its purpose the same may be removed if desired, as the cover, hereinafter to be described, provides a means whereby the frame is securely fastened on the automobile.

The top of the improvement also includes angle side members, and these members 19 are slightly arched. The upper flanges of the side members 19 of the top frame are cut-away at the rear ends thereof, or otherwise gradually reduced so that the said ends may receive therethrough pivots 20 which connect the members 19 to the members 16. The forward and reduced ends of the members 19 are designed to rest against the rear of the top 5 of the roadster 1, as disclosed by the dotted lines in Figure 1 of the drawings.

30 The horizontal flanges of the sides 19 of the top frame are provided with elongated slots or openings 21 and pivoted to the said top flanges, as at 22, there are crossed brace bars 23. These brace bars are pivotally connected, as at 24, and have passed through their free ends bolts 25 which are engaged by winged or like nuts 26. By this arrangement it will be noted that the side members of the top frame may be adjusted with respect 35 to each other so that the same may be arranged upon varying widths of the tops 5 of roadsters, and also that the said arrangement permits of the top frame being telescoped or folded into a small package against the sides 6 when the device is not required for use.

There is arranged around the back frame, and preferably secured thereto by snap fasteners 26' the fabric back of the improvement. The back comprises two sections 27, respectively, the edges of which being inlapping relation and the said sections are provided with spaced alining series of snap fasteners 28 whereby the sections may be adjustably connected. The sections include side flaps 29 which are attached to the rumble seat compartment by snap fasteners 30. The edges of these side flaps 29 are provided with spaced fasteners 31 any one of which is designed to be engaged by cooperating snap fasteners 32 upon the side flaps 33 of the fabric top of the improvement. The fabric top also includes two sections or members having overlapping edges, as disclosed by the dotted lines in Figure 2 of the drawings, and

by the full lines in Figure 4 of the drawings. The cooperating snap fasteners are indicated by the numeral 34. These fasteners are designed to be snapped together when the device is in use. The outer edge of the top as well as the side flaps 33 thereof are provided with snap fasteners 35, to engage with cooperating snap fasteners on the rear of the top 5 of the roadster 1.

Should it be found desirable the top may be swung rearwardly upon its pivotal connection 20 with respect to the back of the improvement to permit of persons entering the rumble compartment and occupying the seat thereof, or the snap fasteners 32 and 30 may be brought out of engagement and one or both of the sides of the fabric back and top covers is thus spread open to admit persons to the rumble compartment.

When not required for use the frame is folded to the position illustrated in Figure 3 of the drawings without necessitating the removal of the rubberized or like fabric coverings from the frame members and the device as a whole may be arranged in a small box-like compartment as indicated by the dotted lines in Figure 3 of the drawings and designated by the character 36. The device may be then arranged in the rumble compartment of the automobile 1. The improvement may be easily and quickly set up to provide an effective protector or cover for the occupants of the rumble seat and when so set up will be rigidly held in position on the automobile. Likewise, the device may be easily and quickly removed from the back of the rumble seat and collapsed or folded into a small package as heretofore described.

Having described the invention, I claim:

A removable and collapsible cover for the rumble seat of an automobile, including a back frame having angle side members, to engage with the rear corners of the back of a rumble seat, an adjustable strap surrounding the frame and guided through the sides and designed to engage with the back of the rumble seat, said sides having their upper corners rounded toward each other, and said sides being formed with elongated slots, flat pivotally connected cross braces, each having one of their ends pivotally secured to the sides, bolt members passing through the second end of the brace members and through the slots in the sides, and nuts engaging such bolts, a top frame which includes arched angle side members that have their rear ends pivoted to the sides of the back and their opposite ends designed to rest on the top at the rear of the automobile, said sides having elongated slots therethrough, pivotally connected cross brace members each having one of their ends pivoted to the sides of the top, bolt members passing through the second ends of the brace members and through the slots of the side members, nuts engaging said bolts, and

fabric covers to enclose the frame sections and to sustain the same on the automobile, said cover comprising a top portion having its rear provided with side flaps, the said top portion having its outer end removably fastened to the top of the automobile and the flaps being removably fastened to the sides of said automobile.

In testimony whereof I affix my signature.

10 EMANUEL WILBANKS.
